(57) **CLAIM**

The ornamental design for the mesh structure for a gas burner, as shown and described.

DESCRIPTION

FIG. 1 is a top perspective view of a burner showing my mesh structure for a gas burner;

FIG. 2 is a bottom perspective view thereof;

FIG. 3 is a top plan view thereof;

FIG. 4 is a front plan view thereof;

FIG. 5 is a bottom plan view thereof;

FIG. 6 is a rear plan view thereof;

FIG. 7 is a side elevation view thereof; and,

FIG. 8 is a side elevation view of the opposite side of FIG. 7; and,

FIG. 9 is my mesh structure for a gas burner without its surrounding environment.

The broken lines shown in the drawings illustrate environment of the mesh structure for a gas burner that form no part of the claimed design.
